UNITED STATES PATENT OFFICE.

ROBERT E. MANLEY, OF YORK, PENNSYLVANIA, ASSIGNOR TO MANLEY MANUFACTURING COMPANY, OF YORK, PENNSYLVANIA, A CORPORATION OF DELAWARE.

GREASE BUCKET.

Application filed December 30, 1924. Serial No. 758,899.

This invention relates to a dispensing appliance adapted for the handling of heavy oils and light greases such as are used in automobile differentials and transmissions. It consists of a grease bucket, a pump centrally located therein, a hose for conveying the grease to some distance from the bucket and a three-way valve for controlling the action of the pump.

10 Figure 1 is a central vertical section through the bucket.

Figure 2 is an almost central vertical section taken at right angles to Figure 1.

Figure 3 is a top plan view.

15 Figure 4 is a horizontal cross section taken at 4—4 in Figure 2 through a three-way valve attached to the bottom of the pump.

The bucket body is built up of sheet metal sides 10, a sheet metal bottom 11, and a ring 20 or three-legged spider 12, which surrounds and strengthens the bucket at the bottom seam. A flanged sheet metal cover 14 is held on by means of lid bolts 15 which project through and hold down a three-armed casting 25 16. This casting 16 is the foundation to which all of the "works" are attached. None of the parts are bolted or fast in any way to the bottom 11. A pump barrel 20 is attached to the center of 16 and projects nearly to the 30 bottom of the bucket and is provided with a piston 21 and a square piston rod 22. The lower end of the pump barrel is attached to a casting 30 which just touches the bottom 11 and extends over to one side of the pump 35 barrel where it is formed so as to serve as the body of a large three-way cock or valve. This body is provided with a plug 32 provided with an operating stem 33 having a handle 34. The plug is provided with two 40 openings and the valve body with three openings. These openings are best seen in Figure 4. 35 leads to the pump body; 36 to the bucket bottom, and 37 to the hose 38. Figure 2 shows the opening 36 leading to a hood 39 with its lip carrying the suction down to very 45 near the bottom of the bucket while the opening 37 leads almost directly to the hose 38. Examining Figure 4 it will be seen that the two openings of the plug will establish connections between the pump barrel and the suction hood or else between the pump barrel and the hose.

50 The pump plunger 22 is provided with a handle 23 at the top for use when a light fluid is being handled, and the ratchet gearing is

not needed. This plunger is square in cross section and is provided with rack teeth 24. A pinion 25 engages these teeth and the pinion is elongated so as to project out to one side of the rack. A back-up or suction pawl 60 27 can engage this elongated portion and likewise the forward or pressure pawl 28 can engage the pinion. These pawls are mounted on a handle 29 and all of the above gearing is mounted on a frame 50 which is bolted to the 65 upper side of the member 16. The sheet metal lid 14 has an opening for filling purposes provided with a lid 51.

A pump barrel 20 is threaded into the casting 16 and a heavy upright flange 41 is located at some distance from the pump barrel 20. Clamping nuts 42 and 43 are necessary to make the fastening of the barrel 20 strong enough. These nuts are provided with notches 44 and 45 and the casting 16 has a few 70 holes (46) drilled through it very near the barrel. Overflow grease will be caught by the flange 41 and can flow through openings 44, holes 46, and openings 45 into the bucket. When using heavy grease the compound 75 ratchet leverage makes it easy to either draw in grease using pawl 27 or discharge the same using pawl 28. The pump is valveless in the sense that it has no pump check valves, all of the controlling of directing of the grease being done by the hand operated three-way 80 valve attached to the bottom of the pump. With this arrangement it is possible to increase the port area greatly over any other 85 type of construction and this permits easy 90 flow and discharge of the oil or grease. Turning the three-way valve so as to connect the pump barrel with the hose and leaving it in that position the grease bucket may be used as a syringe to draw the old lubricant out of 95 a differential or transmission box and then pour kerosene or gasoline over the gears to clean them—after which the kerosene or gasoline may be withdrawn and the differential or 100 transmission box filled with new lubricant. The capacity of the bucket is 25 pounds, as usually constructed, and the stroke of the pump is approximately 12 inches. A pound of grease is sucked in and discharged by one 105 stroke. The usual operation of the device is as follows:

The handle 34 is turned so as to connect the port 35 with port 37, that is, the pump chamber with the suction hood; the pawl 27 is thrown in and the handle 29 manipulated to 110

raise the pump piston 21, thus drawing the pump barrel full of heavy grease; the handle 34 is next turned so as to connect port 35 with port 36, which connects the pump chamber with the hose; pawl 28 is then engaged and the handle 29 manipulated whereupon the pump piston will be forced downwardly, thus compelling the grease to flow from the pump barrel out through the hose.

10. What I claim is:

1. In a portable grease bucket, a fluid container, a cover therefor, a pump centrally mounted on the cover and terminating short of the bottom of the container, a valveless piston in the pump chamber, manual means for reciprocating said piston, mechanism including a gear and ratchet for reciprocating said piston, a flexible hose passing thru the cover and extending into the container and independent of the piston and means within the container for connecting the pump chamber and the hose so that reciprocation of the pump will draw fluid or grease thru the hose into the container or from the container thru the hose as desired.

2. In a portable grease bucket, a fluid container, a cover therefor having drain openings, a pump cylinder secured to said cover, a piston within said cylinder, a rack bar piston rod, means for reciprocating said rack bar and an upstanding annular flange carried by said cover, and surrounding said cylinder and drain openings to direct back into the container any grease or fluid that may escape from the top of the pump cylinder.

3. In a portable grease bucket, a light metal fluid container, a cover adapted to be detachably secured to said container, a pump cylinder secured to said cover, means for reciprocating the pump piston, a casting at the bottom of said pump cylinder and carried thereby, a flexible tube passing thru said cover and secured to said casting, a three-way valve in said casting, a vertical rod secured to said valve and extending thru the cover and adapted to be turned about its axis to connect the pump cylinder with the hose or with the interior of the container, and means upon the cover for supporting the pump chamber,

the casting and the mechanism for operating 50 the pump piston.

4. In a portable grease bucket, a container, a detachable cover therefor, a pump cylinder secured to said cover, a valveless piston in said cylinder, a non-rotatable rack bar secured to 55 said piston, a handle on said rack bar, ratchet and pawl mechanism cooperating with said rack bar to reciprocate the piston, a three-way valve carried by said pump cylinder within the container and a flexible hose passing thru 60 said cover and communicating with said three-way valve whereby grease and oil may be discharged into or sucked from an automobile differential.

5. In a device for handling heavy oils and 65 soft greases, a sheet metal bucket, a legged base surrounding and strengthening the bucket at the bottom, a flanged sheet metal cover, lid bolts secured to the bucket and projecting thru said cover, an armed casting held 70 against said cover by said lid bolts, and measuring and discharging mechanism carried by said casting for measuring grease taken into or discharged from said bucket.

6. In a portable grease bucket, a container, 75 a cover therefor, a pump cylinder passing thru said cover, nuts securing said cylinder to said cover and an annular flange extending upwardly from said cover, said nuts having 80 passageways therethrough and there being a 80 passageway between the pump cylinder and the cover whereby any overflow of grease from the pump cylinder will be caught by the flange and be directed thru said openings back into the container.

7. In a portable grease bucket, a container, a cover therefor, a pump carried by said cover and extending into the container, manual means for reciprocating the pump, and geared means also for reciprocating the 90 pump whereby grease may be pumped ordinarily by the hand operated means and the mechanical means may be used when pumping against a pressure or when heavy fluid is being handled.

In testimony whereof I affix my signature.

ROBERT E. MANLEY.
